UNITED STATES PATENT OFFICE.

WILLIAM E. ELLIOTT, OF GRAND RAPIDS, MICHIGAN.

WASHER FOR BUTTON ATTACHMENTS.

1,220,829.

Specification of Letters Patent.

Patented Mar. 27, 1917.

Application filed March 4, 1916. Serial No. 82,234.

To all whom it may concern:

Be it known that I, WILLIAM E. ELLIOTT, a citizen of the United States of America, residing at Grand Rapids, in the county of Kent and State of Michigan, have invented certain new and useful Improvements in Washers for Button Attachments; and I do hereby declare the following to be a full, clear, and exact description of the invention, such as will enable others skilled in the art to which it appertains to make and use the same.

This invention relates to a washer for use in attaching buttons to sections of fabric, leather or the like. In the attachment of buttons, and especially shoe buttons, by means of wire staples to leather, imitation leather or fabric materials such for instance as is used in the manufacture of leggings and the like the clenching of the staple through the material forms a permanent connection for the button so long as the material does not become disrupted and destroyed adjacent the staple. In practice, however, the severity of usage to which said material is subjected ordinarily suffices in a short time to pull the staple through the material. It is the object and purpose of the present invention to provide a device which may be used in connection with the attaching staple to protect the material at the point of attachment, the strain to which the staple is subjected being transmitted to said device and in turn transmitted from said device to the material but over a much wider area than in the case where the staple is attached directly to said material. A further object of the invention consists in the provision of a device of this character in which the legs of the staple may be bent inwardly and to a large degree be housed by the device so that said legs will not bear against the person when the article to which it is attached is worn. Various other objects and purposes together with novel construction for attaining the same will be apparent upon understanding of the invention disclosed in the accompanying drawing, in which;

Figure 1 is a view illustrating the attachment of a button to a section of material.

Fig. 2 is a similar view taken from the side of Fig. 1.

Fig. 3 is a transverse section through the attaching washer, the position taken by the staple when attached being indicated in dotted outline.

Fig. 4 is a section on the line 4-4 of Fig. 5.

Fig. 5 is a plan view of the attaching washer; and

Fig. 6 shows the manner in which the washer is produced commercially in large numbers.

Like reference characters refer to like parts throughout the several views of the drawing.

My invention is shown in the application of attaching a shoe button to a section of material such as leather, fabric or the like, the button having a head 1 and an eye 2 as is usual and the section of material being indicated at 3. For attachment of the button to the material a wire staple is used having a central loop 4 in which the wire comprising the eye 2 of the button may seat and depending spaced apart legs 5 which when attached are bent inwardly toward each other and clenched against the underside of the material as illustrated in Fig. 2.

The washer 6 used in connection with the attaching staple is formed of thin metal and cut substantially circular in outline, the edge being formed with an annular inturned lip 7 which bears against the underside of the fabric. The central portion of the washer is depressed as illustrated and at diametrically opposed points openings 8 are provided to permit the passage of legs 5 of the staple. There is also provided a central opening 9 which lies midway between the openings 8 and furthermore the metal between openings 8 and 9 at each side is embossed to form grooves 10 as shown. In addition I prefer to cut openings 11 at diametrically opposed points in the washer and situated from the openings 8 a distance substantially equal to an arc of 90 degrees between which and the central opening 9 there may also be formed grooves 10^a identical in form with grooves 10 heretofore described.

With a washer of this character located on the underside of the material 3, the legs 5 of the staple pass through the opening 8 and are clenched against the washer, the legs occupy the grooves 10 or 10^a while the extreme ends thereof come together at the opening 9 and may partially enter such opening, it being apparent that with this construction the ends of the legs 5 are bent so as to lie below the outer surface of the washer and are practically housed thus insuring against discomfort to the wearer.

The four openings 8 and 11 are made in the washer so that it may be guided and held in place on any suitable tool for attaching the button and washer to the section 5 3, this tool being of a type similar to any of the well known staple clenching tools used for attaching buttons with wire staples to shoes or like articles, the under jaws of which may be provided with suitable projections to enter the openings 8 or 11 not 10 used for the passage of the legs of the staple to properly locate the washer.

In the practical manufacture of the washers they are stamped in a continuous strip 15 from a strip of metal and as illustrated in Fig. 6 are formed at one operation each being tied to an adjacent washer by a tie 12 which, when the washer is used, is easily and readily severed therefrom. When thus 20 made the additional openings 11 and grooves 10^a will not be necessary, these being of value in individual washers for the purpose of locating a single washer in a hand tool but not in a continuous strip in 25 which the position of the strip will serve to properly locate any washer for attachment.

I claim:

1. In combination, a button having an eye 30 adapted to be located on one side of a section of material, a washer adapted to be located on the opposite side of said material, said washer being formed of a thin circular piece of metal with a central opening and a pair of diametrically opposed openings positioned adjacent the edges of the washer, an annular lip bent from the washer toward the material, grooves formed in the washer on the outer side thereof, said grooves lying between the central opening 35 and each of the other openings in the washer, and a staple inserted through the eye of the button with a leg passing through each of the pair of openings, said legs being clenched against the washer and seated 40 in the grooves therein, with the ends of the legs partially entering the central opening.

2. In combination, a button having an eye 45 adapted to be located on one side of a section of material, a washer adapted to be located on the opposite side thereof, said

washer being formed from thin metal provided with a central opening and a pair of openings located equally distant from and on opposite sides of the central opening, a staple inserted through the eye of the button, the legs of the staple being adapted to pass through the material and the pair of openings in the washer and clenched against said washer, said washer also being formed with means to receive and partially house 60 the parts of the legs clenched thereagainst.

3. In combination, a button having an eye adapted to be located on one side of a section of material, a washer adapted to be located on the opposite side thereof, said washer having 65 a central opening and a pair of openings on opposite sides of and equally spaced from the central opening, and a staple inserted through the eye of the button with its legs adapted to pass through the material and pair of openings in the washer, said legs being turned inwardly toward each other and against the washer with the ends of the legs partially received in the central opening of 70 the washer.

4. A washer for use in the manner described, comprised of a circular piece of thin metal and provided with a central opening and diametrically opposed openings spaced equally from the central opening, an annular lip turned to project from the edges of the washer, said central portion of the washer being depressed and formed with grooves between the central opening and each of the other openings, 80 substantially as described.

5. A washer for use in the manner described, formed from thin metal and provided with a central opening and four additional openings positioned around the 90 central opening substantially equal distances from each other, said washer also having grooves in alignment formed therein between the central openings and each of two of the additional openings, substantially as described.

In testimony whereof I affix my signature.

WILLIAM E. ELLIOTT.
